UNITED STATES PATENT OFFICE

CARSON R. STEWART, OF BURGHILL, OHIO

GARDEN MARKER

Application filed August 5, 1931. Serial No. 555,263.

This invention relates to garden markers such as commonly are used to identify various varieties of stock in home or commercial gardens, and more especially it relates to garden markers consisting of two pieces, namely, a stake and a name plate.

The chief objects of the invention are to provide a marker of the character mentioned having a name plate that may be read from standing position; to provide against loss of the name plate; to provide a marker that will lie flat so that it may be used conveniently to identify stock in storage; and to provide a marker construction which will permit pounding of the stake to insert it in the ground without danger of damage to the name plate. Other objects contemplated are simplicity of construction, ruggedness to withstand handling and the action of the elements, universal applicability, and low cost of manufacture.

Of the accompanying drawing;

Figure 1 is a plan view of the improved marker as it appears in use in a garden;

Figure 2 is a side elevation thereof; and

Figure 3 is a detail side elevation on a larger scale, parts being broken away and in section.

Referring to the drawing, the improved marker consists of a wire stake 10 having its upper end portion formed into an integral loop or eye 11, and 12 is a metal name plate that is formed at one end with an end-slot 13 and an aperture 14 adjacent said slot, said name plate being permanently mounted upon the eye portion 11 of the stake.

The eye of the stake defines a generally ovate figure, the short axis of which is substantially the same length as the distance between adjacent edges of the slot 13 and aperture 14 of the name plate. The walls of the slot 13 and aperture 14 are perpendicular to the respective faces of the name plate, and their marginal corners are square and sharp.

The stake structure constituting the eye 11 extends through the slot 13 and aperture 14 of the name plate, the arrangement being such that the slot 13 permits free movement of the plate for about 180 degrees about the end of the stake, further movement in either di-

rection being prevented by the wedging of that portion of the name plate between the slot and aperture into widest portion of the short axis of the eye 11, as is most clearly shown in full lines in Figure 3. It will also be observed that the provision of the slot 13 assures that movement of the name plate about the end of the stake is substantially in a single plane, which plane is transverse to the plane of the name plate.

Thus the name plate normally is disposed in horizontal position at right angles to the stake 10 when the latter is mounted upright in the ground. The name plate easily is turned to position parallel to the stake 10, as indicated by the broken lines in Figure 2, upon occasion such as when the marker is placed with stock in storage, and the length of the slot 13 is such that the eye structure cannot escape therefrom, in any position of the name plate.

The marker may be constructed of galvanized iron, aluminum, or other suitable metal capable of resisting corrosion by the elements. The name of the stock variety may be stamped into the name plate, or it may be written thereon with wax crayon and still be legible after two or three seasons.

The name plate cannot become separated from the stake, and indicia thereon always is easily readable from a standing posture.

Modifications may be resorted to within the scope of the appended claims which are not limited wholly to the specific construction shown and described.

What is claimed is:

1. A garden marker comprising a name plate and a stake, said name plate being formed at one end with an aperture and a slot, and said stake being formed on one end with a loop or eye that is so shaped and extended through the aperture and slot of the name plate as to effect determinate limited positionability and mobility of the latter with relation to the stake.

2. A garden marker comprising a name plate and a stake, said name plate being formed adjacent one end with an aperture, and said stake being formed at one end with a loop or eye that extends through said aper-

ture, the dimensions and shape of the eye being so related to the distance of the aperture from said end of the name plate that the latter normally assumes a horizontal position by engagement of said end with the walls of the loop when the stake is positioned upright in the ground.

3. A garden marker as defined in claim 2 in which the name plate is movable in an arc of substantially 180 degrees about the end of the stake.

4. A garden marker comprising a name plate and a stake, said name plate being formed with an aperture adjacent an end thereof, and said stake being formed at one end with a loop or eye that extends through said aperture, said eye being of ovate shape and having a short axis of determinate length with relation to the position of the aperture in the name plate whereby the latter has determinate limited positionability about the end of the stake due to engagement of said end of the name plate with said loop.

5. A garden marker comprising a name plate and a stake, said stake being formed at one end with a loop or eye, and the name plate being formed with an aperture adjacent an edge thereof by means of which it is mounted upon the eye of the stake, said edge on the name plate cooperating with the stake to limit movement of the name plate with relation to the stake substantially to a single plane.

6. A garden marker comprising a name plate and a stake, said name plate being formed with an end slot and an aperture adjacent said slot, and said stake being formed at one end with a loop or eye that extends through said slot and aperture in the name plate, said loop being of ovate shape and having a short axis of determinate length with relation to the distance between the end slot and aperture of the name plate whereby the latter has limited movement of about 180 degrees about the end of the stake.
